(57) **CLAIM**

The ornamental design for a chest and arm garment, as shown and described.

DESCRIPTION

FIG. 1 is a front view of a chest and arm garment, on an environmental human depiction, in accordance with the claimed design;

FIG. 2 is a front view of the design of FIG. 9;

FIG. 3 is a rear view of the design of FIG. 9;

FIG. 4 is a left view of the design of FIG. 9;

FIG. 5 is a right view of the design of FIG. 9;

FIG. 6 is a bottom view of the design of FIG. 9;

FIG. 7 is a top view of the design of FIG. 9; and,

FIG. 8 is a top left perspective view thereof.

The dash-dash broken lines in the figures represent environmental subject matter, and form no part of the claimed design.

The symbolic break lines (e.g., pairs of dash-dash broken lines) immediately adjacent the solid lines represent a boundary between claimed and unclaimed subject matter and form no part of the claimed design. The appearance of any portion of the article between the break lines forms no part of the claimed design.

The surface shade lines in the figures show contour, and do not indicate any surface ornamentation, opacity, or translucency.

1 Claim, 8 Drawing Sheets
